(57) **CLAIM**

The ornamental design for a dispenser for E-liquid, as shown and described.

DESCRIPTION

FIG. 1 is a right side, top perspective view of a dispenser for E-liquid embodying our new design;

FIG. 2 is a front elevation view thereof;

FIG. 3 is a back elevation view thereof;

FIG. 4 is a left side view thereof;

FIG. 5 is a right side view thereof;

FIG. 6 is an enlarged top plan view thereof; and,

FIG. 7 is an enlarged bottom plan view thereof.

The broken lines in the figures depict the portions of the dispenser for E-liquid that form no part of the claimed design.
